(57) **CLAIM**

The ornamental design for a dental dispenser platform, as shown and described.

DESCRIPTION

FIG. 1 is a top-front-left perspective view of a dental dispenser platform showing my new design;
FIG. 2 is a bottom-rear-right perspective view thereof;
FIG. 3 is a bottom-front perspective view thereof;
FIG. 4 is a left-side elevational view thereof;
FIG. 5 is a right-side elevational view thereof;
FIG. 6 is a front elevational view thereof;
FIG. 7 is a rear elevational view thereof;
FIG. 8 is a top plan view thereof;
FIG. 9 is a bottom plan view thereof;
FIG. 10 is a detail view of area 10 in FIG. 1; and,
FIG. 11 is a detail view of area 11 in FIG. 4.

The dashed line showing a user interface system in FIGS. 1, 3, 4, 5, 6, 8, and 9; an access panel with suction cups in FIGS. 2, 4, 5, 7, 8, and 9; a cup dispenser in FIGS. 1, 2, 3, 5, 6, 7, 8, and 9; a mounting post in FIGS. 1, 4, 7, 8, 10, and 11; and a mounting indentation in FIGS. 1, 8, and 10 is included for the purpose of illustrating environmental structure and forms no part of the claimed design.
